UNITED STATES PATENT OFFICE.

HARLAN S. RECTOR, OF CHICAGO, ILLINOIS.

DESIGN FOR A TIRE.

56,766.

Specification for Design.

Patented Dec. 14, 1920.

Application filed October 27, 1919. Serial No. 333,857. Term of patent 7 years.

To all whom it may concern:

Be it known that I, HARLAN S. RECTOR, a citizen of the United States, residing at Chicago, in the county of Cook and State of Illinois, have invented a new, original, and ornamental Design for a Tire, of which the following is a specification, reference being had to the accompanying drawing, forming a part thereof.

In the drawing: Figure 1 is a perspective

of a portion of a tire embodying the new design. Fig. 2 is a side elevation. Fig. 3 is a transverse section.

The invention is characterized by having projections on substantially all portions of the tire except the base.

I claim:

The ornamental design for a tire as shown.

HARLAN S. RECTOR.
